UNITED STATES PATENT OFFICE

114,170

DESIGN FOR A DISPLAY STAND

Alfred O. Bowen and Fleety E. Taylor,
East Gadsden, Ala.

Application August 16, 1938, Serial No. 79,383

Term of patent 14 years

To all whom it may concern:

Be it known that we, Alfred O. Bowen and Fleety E. Taylor, citizens of the United States of America, each residing at East Gadsden, county of Etowah, State of Alabama, have invented a new, original, and ornamental Design for a Display Stand, of which the following is a specification, reference being had to the accompanying drawing, forming a part thereof, wherein:

We claim:

The ornamental design for a display stand, as shown.

ALFRED O. BOWEN.
FLEETY E. TAYLOR.
